UNITED STATES PATENT OFFICE.

ISAAC SNOW, OF LAWRENCE, MASSACHUSETTS, ASSIGNOR TO HOPEDALE MANUFACTURING COMPANY, OF MILFORD, MASSACHUSETTS, A CORPORATION OF MASSACHUSETTS.

FILLING-FEELER MECHANISM FOR LOOMS.

Application filed November 1, 1919. Serial No. 334,948.

To all whom it may concern:

Be it known that I, ISAAC SNOW, a citizen of the United States, residing at Lawrence, in the county of Essex and State of Massachusetts, have invented certain new and useful Improvements in Filling-Feeler Mechanisms for Looms; and I do hereby declare the following to be a full, clear, and exact description of the invention, such as will 10 enable others skilled in the art to which it appertains to make and use the same.

This invention relates to an improvement in filling feeler mechanisms for looms.

One object of the invention is to reorganize the construction of filling feeler mechanisms for looms in order to produce a novel, simple, compact and efficient form thereof. To the accomplishment of this object, the invention consists in the filling feeler mechanism hereinafter described and claimed.

In the drawings illustrating the preferred embodiment of the invention, Fig. 1 is a plan, Fig. 2 is a side elevation of the filling feeler mechanism in its normal or inoperative position; Fig. 3 is a horizontal section showing the positions assumed by the feeler member at the extreme forward beat of the lay before critical exhaustion of the filling occurs; Fig. 4 is a view similar to Fig. 3 at critical exhaustion of the filling in the filling carrier; Fig. 5 is a diagrammatical illustration showing the connections between the filling feeler mechanism and the loom controlling devices.

The loom to which the improved filling feeler mechanism is applied may be of any usual or preferred construction and may be either a plain loom or a weft replenishing loom. If applied to a plain loom, the filling feeler mechanism operates upon critical exhaustion of the filling to cause loom stoppage, and if applied to a weft replenishing loom the filling feeler mechanism operates upon critical exhaustion of the filling to cause the insertion of a fresh supply of filling in the shuttle. In Fig. 5 of the drawings the filling feeler mechanism is illustrated diagrammatically as applied to a weft replenishing loom.

The filling feeler mechanism illustrated in the drawings is described as follows: The filling feeler member 10 is mounted and adapted to reciprocate upon a support 30 and is provided with an oscillatory nose 13.

A movable arm 15 is mounted upon the fill-

ing feeler member 10 and is arranged to cooperate with the oscillatory nose 13 so as to be moved outwardly thereby beyond the side of the filling feeler member 10, whenever the nose is oscillated in one direction. 60 The construction and arrangement of the feeler member 10 is such that whenever the same is moved forward bodily, torque is applied to the nose 13 in a manner as will be described, producing a positive tendency to oscillate the nose 13 in such a manner as to move the arm 15 into its projecting position beyond the side of the feeler member 10. The nose 13 is provided with a series of filling engaging teeth 16 which are adapted to engage the filling in the filling carrier when the lay beats up and by means of which the oscillation of the nose 13 is either prevented or permitted according to the condition of the filling in the filling carrier. When critical exhaustion occurs as the lay beats up, the nose 13 is brought into contact with the filling in the filling carrier, the contour of which permits the oscillation of the nose 13 70 in a direction towards the butt of the spindle so that the movable arm 15 is immediately moved into its projecting position. As the lay continues to beat up the forward movement of the projecting arm 15 therewith, is utilized to initiate the operation of the loom 75 controlling devices so that if the filling feeler mechanism is applied to a weft replenishing loom as diagrammatically illustrated in Fig. 5, the movement of the arm 15 operates to initiate the weft replenishing 80 operation. The connections between the feeler member 10 and the loom controlling devices are the same as are usually employed for this purpose and inasmuch as they form no part of the present invention, further description is omitted. The shuttle is provided 85 with the usual slot in the side wall thereof, through which the feeler member 10 may enter to feel for the filling and the operation of the weft replenishing mechanism is as usual and is familiar to those skilled in the art.

The improved filling feeler mechanism comprises a support 30 adapted to be secured by the bolts 31 to the breast beam of the loom. The support 30 comprises an open ended casing 33 through which the feeler member 10 reciprocates and by which its reciprocations are confined to a straight path. The feeler member 10 comprises two 100

plates 40, 41, one of which is provided with bosses 45, 46, extended from the surface thereof and upon which the oscillatory nose 13 and movable arm 15 are pivotally mounted. The plates 40, 41, are maintained in spaced relation by the bosses 45, 46, 55, and are prevented from relative longitudinal movement by studs 42, 43, extended from the upper plate 40 which cooperate with holes 10 in the lower plate 41.

The lower plate 41 of the feeler member 10 is provided at the end remote the nose 13 with a boss 55, which serves as a bearing for the forked end of a rod 56. The other 15 end of the rod 56 slides through a hole in an upturned bracket 58 which is extended from the surface of the support 30 and a coil spring 57 embracing the rod 56, serves to yieldingly hold the feeler member 10 in a 20 rearward position with the nose 13 extended as shown in Fig. 1. After the feeler member 10 has been moved forwardly by contact with the filling as the lay beats up, the compression thus set up in the coil spring 25 57 operates, upon the backward beat of the lay, to return the feeler member to its original position. The casing 30 is provided with a slot in one side thereof through which the arm 15 may project beyond the side of 30 the feeler member. The other side of the casing is closed by a bar 59 normally secured in fixed relation to the casing by pins 69. The end of the bar is turned inwardly and provided with a hole through which a rod 35 60 slidingly passes.

The oscillatory nose 13 comprises a circular disk having a series of filling engaging teeth 16 in one portion of the periphery thereof, and with a segmental gear 51 in another portion of its periphery. The 40 movable arm 15 is provided with a segmental gear 52 meshing with the segmental gear 51, of the nose 13, and the centers of the bosses 45, 46, are spaced at such distance from one 45 another that the gears 51, 52, may properly mesh so that when the nose 13 is oscillated the movable arm 15 is swung on its pivot.

Whenever the filling engaging teeth 16 are brought into contact with the filling as 50 the lay beats up, the feeler member 10 is bodily moved forward therewith. The forward movement of the feeler member 10 is utilized to produce a positive tendency to oscillate the nose 13. For this purpose the rod 55 60 is provided with a head 65 received in a recess in one side of the nose 13. The rod 60 is yieldingly held from movement so that when pressure is exerted by the filling upon the nose 13, the resistance to movement exerted by the rod 60 through the head 65 causes the nose 13 to tend to oscillate. The end of the rod 60 remote the nose 13 is upturned and connected by a coil spring 61 with one arm 60 of a bell crank 62 pivoted upon the pin 69 secured in the support 30. The other arm 65

of the bell crank 62 is provided with a pin 68 which is adapted to engage and fit into a recess 66 in the side of the rod 60. The arrangement of the bell crank 62, spring 61 and rod 60, as clearly shown in Fig. 1, 70 is such that the rod is yieldingly held rearwardly and so that its forward movement is resisted by engagement of the pin 68 with the recess 66. The nose 13 is provided with a shoulder 67 which is adapted to cooperate 75 with one side of the rod 60 to limit thereby the rotation of the nose about its pivot in one direction and is further provided with a bearing surface 70 adapted to cooperate with the other side of the rod 60 to limit the 80 rotation of the nose in the reverse direction, as shown in Figs. 3 and 4 respectively. It will, therefore, be observed that when the filling engaging teeth 16 are struck by the filling and the feeler member 10 is started 85 upon its bodily forward movement, the nose 13 is oscillated (when the presence of filling does not prevent) from its position shown in Fig. 1 to the position shown in Fig. 4, in which position the bearing surface 70 is 90 brought against the side of the rod 60 thereby limiting further oscillation of the nose 13. As the lay continues to beat up and the feeler member 10 is moved forward bodily, the rod 60 being also moved forwardly causes 95 the pin 66 to ride up out of the recess and along the surface of the rod into the position shown in Fig. 4 thus increasing momentarily the tension in the spring 61 and thereby increasing the tendency of the nose 100 100 to rotate. In this position the arm 15 projects beyond the side of the feeler member 10 and the feeler member 10, nose 13, rod 60 and arm 15 are all in extreme forward positions of their stroke.

As the lay beats backward, the feeler member 10 and associated parts are also moved backward by the compression in the coil spring 57 and the position of the arm 15 and rod 60 remain as indicated in Fig. 4 110 until near the end of the rearward stroke of the feeler member. At this point the upturned end of the rod 60 strikes the end of the block 59 thereby preventing further rearward movement of the rod 60. The continued rearward movement of the feeler member 10 causes the oscillation of the nose 13 from a position similar to that indicated in Fig. 4, to a position as is indicated in Fig. 3, thereby causing the arm 15 to return 115 from its projected position to its normal or inoperative position, as is shown in Fig. 1.

The cooperation of the bodily movement of the feeler member 10 with the rod 60 to produce the above described oscillation of the nose 13 may be compared to the rolling of a wheel upon the ground. In such a comparison, the pivot of the nose 13 is the axle of the wheel and the head 65 of the rod 60 is the ground. When considered in 120 125 130

this manner, it will be seen that as the axle or pivot is moved in a straight line path, the point of contact of the wheel with the ground (or in other words, the rod 60 being held stationary) causes the rotation of the nose 13 about the head 65 as a center so that each time the feeler member 10 is moved forward bodily, a positive torque is applied to the nose by the head 65 of the rod 60.

10 The operation of the filling feeler mechanism is described as follows: As the lay beats up and the teeth 16 of the nose 13 engage the filling in the filling carrier, the normal tendency of the nose 13 to oscillate is either prevented by the contact of the teeth with the filling or, on the other hand, is permitted if the filling is critically exhausted from the bobbin. At critical exhaustion, the contour of the filling in the 20 filling carrier may present the usual bunch, if the bobbin has been wound with a preliminary bunch or on the other hand, the filling may be exhausted to such an extent that there is not a sufficient portion thereof remaining upon the bobbin to engage the teeth 16 and to prevent the normal tendency of the nose 13 from oscillation. When the bobbin is wound with a preliminary bunch and the filling is exhausted to the bunch, it 30 will be observed that the portion of the teeth to the right of the central axis of the feeler member 10, viewing Fig. 1, will engage the filling before the portion of the teeth to the left of the axis, thereby permitting the oscillation of the nose 13, through the above described cooperation of the head 65 of the rod 60 and the forward movement of the feeler member 10.

When filling is present during the normal 40 operation of weaving, the engagement of the portion of the teeth to the left of the axis of the feeler member 10, viewing Fig. 1, prevents the oscillation of the nose 13 so that as the lay continues to beat up, the feeler member and rod 60 are bodily moved from the position indicated in Fig. 1 to the position indicated in Fig. 3 with the arm 15 in its inoperative position, so that the reciprocations of the feeler member 10 do not initiate the operation of the loom controlling devices.

While the preferred embodiment of the invention has been illustrated and described, it will be understood that the same may be embodied in other forms within the scope of the following claims:

1. A loom having, in combination, loom controlling devices, a filling carrier and a filling feeler mechanism comprising a support secured to the loom frame, a feeler member movably mounted thereon having a movable arm, a movable nose, and connections between the arm and nose whereby

movements of the nose cause movements of the arm, said feeler member having provision whereby the movements of the feeler member are utilized to cause movements of the nose unless prevented by the filling in the filling carrier. 65

2. A loom having, in combination, a lay, 70 a filling carrier and a filling feeler mechanism comprising a support, a feeler member slidably mounted thereon, a filling engaging nose rotatably mounted on the feeler member, a device carried by the feeler member cooperating with the filling engaging nose arranged to yieldingly hold one portion of the nose from reciprocatory movement with the feeler member as the latter is moved on the forward beat of the lay, to thereby cause rotation of the nose unless prevented by the filling in the filling carrier, and a lever arranged to be moved into operative position 75 when the nose is so moved. 80

3. A loom having, in combination, a lay, 85 a filling carrier and a filling feeler mechanism comprising a support, a feeler member slidably mounted thereon, a filling engaging nose rotatably mounted on the feeler member, a device carried by the feeler member cooperating with the filling engaging nose arranged to yieldingly hold one portion of the nose from reciprocatory movement with the feeler member as the latter is moved on the forward beat of the lay, to thereby cause rotation of the nose unless prevented by the filling in the filling carrier, a lever arranged to be moved into operative position when the nose is so moved, and means for limiting 90 the extent of rotation of the nose so that after the lever has been moved into an operative position the feeler member, nose and lever are thereafter moved as the lay continues to beat up. 95

4. A loom having, in combination, a lay, 100 a filling carrier and a filling feeler mechanism comprising a support, a feeler member slidably mounted thereon, a filling engaging nose rotatably mounted on the feeler member, a device carried by the feeler member cooperating with the filling engaging nose arranged to yieldingly hold one portion of the nose from reciprocatory movement with the feeler member as the latter is moved on the forward beat of the lay, to thereby cause rotation of the nose unless prevented by the filling in the filling carrier, and a lever arranged to be moved into operative position when the nose is so moved, 105 said device being arranged to limit the extent of rotation of the nose so that after the lever has been moved into an operative position the feeler member, nose and lever are thereafter moved as the lay continues to beat up. 110
